(57) **CLAIM**

The ornamental design for a development cartridge, as shown and described.

DESCRIPTION

FIG. 1 is a perspective view of a development cartridge of the present invention;

FIG. 2 is another perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a perspective view of a development cartridge according to a second embodiment of the present invention;

FIG. 10 is another perspective view thereof;

FIG. 11 is a front view thereof;

FIG. 12 is a rear view thereof;

FIG. 13 is a top plan view thereof;

FIG. 14 is a bottom plan view thereof;

FIG. 15 is a right side elevational view thereof;

FIG. 16 is a left side elevational view thereof;

FIG. 17 is a perspective view of a development cartridge according to a third embodiment of the present invention;

FIG. 18 is another perspective view thereof;

FIG. 19 is a front view thereof;

FIG. 20 is a rear view thereof;

FIG. 21 is a top plan view thereof;

FIG. 22 is a bottom plan view thereof;

FIG. 23 is a right side elevational view thereof;

FIG. 24 is a left side elevational view thereof;

FIG. 25 is a perspective view of a development cartridge according to a fourth embodiment of the present invention;

FIG. 26 is another perspective view thereof;

FIG. 27 is a front view thereof;

FIG. 28 is a rear view thereof;

FIG. 29 is a top plan view thereof;

FIG. 30 is a bottom plan view thereof;

FIG. 31 is a right side elevational view thereof; and,

FIG. 32 is a left side elevational view thereof.
